UNITED STATES PATENT OFFICE.

CHAUNCEY BLAIR FORWARD, OF URBANA, OHIO.

PROCESS OF REFINING OIL.

Application filed January 9, 1919. Serial No. 270,408.

To all whom it may concern:

Be it known that CHAUNCEY BLAIR FORWARD, a citizen of the United States, residing at Urbana, in the county of Champaign and State of Ohio, has invented certain new and useful Improvements in a Process of Refining Oil, of which the following is a specification.

My invention relates to a process of refining oil, which is an improvement on the process for treating oil shown and described in my application Ser. No. 205,815, filed December 6, 1917. In practicing this improved process, crude oil or any fractional distillate thereof is separated into its component parts by the application of superheated steam together with the waste heat or flue gases of the boilers or furnaces which generate and superheat the steam. The preferable sequence of steps taken involve initial heating of the oil by the waste heat or flue gases of the boiler or furnace producing or superheating the steam, and secondly, a further heating of the oil to a higher temperature by the application of the superheated steam. In these proceedings the temperature of the waste heat or flue gases as applied is below the point where coking or carbonizing of the oil and fouling of the apparatus can occur, and the application of the superheated steam is also within predetermined temperatures to effect separations without coking or carbonizing the oil. Other steps which expedite the separations and effect economy in consumption of fuel and make the process of practical value and utility commercially, consist in delivering the steam from a single boiler to separate sets of oil heaters and separators, in superheating the steam repeatedly for use in the separate sets of oil heaters, in utilizing the superheated steam in the final oil heater of each set to atomize the oil and effect separations in the primary separators, and in treating the vapors with a measured flow of water to effect various fractional separations continuously.

In the accompanying drawing, Figs. 1 and 2 are side and plan views, respectively, of a system and apparatus wherewith to practice my improved process on a commercial scale, and Fig. 3 is an enlarged view of a portion of the apparatus. As shown, I use a steam boiler 2 and a main steam superheater 3 in connection with a plural number of oil preheaters 4, 5 and 6, re-

spectively, arranged in sets, together with a series of auxiliary steam superheaters 7, Boilers 2 may be of any desirable construction and type adapted to supply steam at a high temperature of 900 degrees F. or higher, either by a superheater 3 separate and apart from the boiler, or the superheating may be done by suitable coils placed within the furnace itself, substantially as shown in my Letters Patent Number 1,251,850. In either event the steam is raised to a high temperature at a definite cost in fuel, and with a certain amount of waste heat or escape of flue gas. To utilize this waste heat so as to work economy in the application of the superheated steam in separating the oil into fractional distillates, I place a coil 8 of oil-conveying pipe in the path of the flue gases from boiler 2 and as shown this coil is placed at the bottom of the boiler stack S. The superheater is also shown as discharging hot gases into the stack above and below the coil by way of separate pipes P—P' having separate dampers D—D', respectively, so that these hot gases may be also utilized if desired. The temperature of the waste gas discharged at this point is high enough to heat the oil very materially as it flows continuously through coil 8 but there is no excessive heating of the coil throughout its length or in spots or localized areas therein to cause coking or burning of the oil and fouling of the pipe. Waste gas at a temperature between 500 and 600 degrees F. may be safely used in heating the cold oil as a preliminary step in operations, or if the flue gas exceeds such temperatures it may still be used with reasonable safety, and this heated oil flows under pressure through a pipe 9 to a main or header 10 having a series of branch distributing pipes 11 leading to the different sets of oil heaters which are heated by steam.

Each heater 4, 5 and 6, respectively of each set, comprises a closed cylinder containing a coil of pipe many hundred feet in length, and the pipe itself is of relatively small diameter. The heated oil passes from the branch pipe 11, first, into and through the coil in heater 4, thence into and through the coil in the second heater 5, and finally into and through the coil in the third heater 6, and this course of the oil is the same in each set of heaters. Further, a pipe 14 conveys the heated oil from the coil in heater 6 to an

atomizer 15 which is adapted to discharge the oil in an atomized state into a relatively small cylinder or separator 16 together with superheated steam at a high temperature. The steam is conveyed to the atomizer through a pipe 17 connected with the cylinder or third heater 6, and a supply of superheated steam at a very high temperature, to wit, between 800 or 900 degrees F. or higher, is delivered direct to each cylinder 6 from the main superheater 3 by way of a main supply pipe 18 and its branches 19. The second heater 5 in the first set of the series of oil heaters also receives its supply of steam directly from main superheater 3, but the remaining oil heaters, to wit, heater 4 of the first set and heaters 4 and 5 of each of the succeeding sets, are heated by the steam discharged from cylinder 5 of the first set. However, steps are taken to raise the temperature of the steam after using the same in the first set and before using it in the second set of cylinders, a proceeding which is manifestly necessary in view of the transference of heat from the steam to the oil passing in an opposite direction through each set of oil heaters. This reheating of the steam is obtained by an auxiliary superheater 7, one for each set of oil heaters except the first set, and the first auxiliary superheater is located in the pipe line between the first and second sets of oil heaters, while the second auxiliary superheater is placed in the pipe line between the second and third sets of oil heaters, and so on to the highest number or amount. The first superheater 7 reheats the steam used in cylinders 4 and 5 of the first set so that the steam may be used effectively in the second set of oil heaters, and the second superheater repeats this step of raising the temperature of used steam so that it may be used again in the third set of oil heaters and so on to the end within practical limits. The steam is carried forward from set to set of oil heaters under the pressure derived from the single boiler 2, and by the successive reheating steps as described the same steam may be used repeatedly and effectively in connection with the waste heat so as to heat the oil to high temperatures without ill effect on the oil and apparatus. Moreover, there is a material saving in fuel and steam in large commercial operations as compared with the steps taken by me heretofore.

The superheated steam, after its use in the last cylinder or preheater 6, is lowered somewhat in temperature, but in view of the fact that the oil has been brought to a high temperature before flowing through the coil in this last cylinder or preheater 6 the fall in temperature is not very great and the steam is still available for efficient use at the atomizer 15, where it is discharged into the primary separator 16 with the oil and vapors

and where the separation of the vaporized and unvaporized portions of the oil occur. The more volatile constituents pass upwardly and out of the separator through pipe 20, while the heavier portions are precipitated to the bottom of the separator 16 and discharged by the pressure therein through the drain pipe 21 into a residuum tank 22 which may be located at a distant point or wherever most convenient. 75

The next step in operations consists in subjecting the volatile product to a cleansing or clarifying action while also effecting further separation by condensing parts thereof into one or more useful fractional distillates. This is accomplished by discharging the volatile product from pipe 20 into the bottom of an upright cylinder 23 and spraying the rising vapors with a measured amount of water, then passing the remaining volatile portion through a pipe 24 to the bottom of a second cylinder 25 wherein the same spraying treatment is given. In the present drawings, three more cylinders 26, 27 and 28, respectively, are connected to operate in the same way, making five clarifying separators connected in tandem to effect five separations before the vapor from which gasoline is derived passes through a pipe 29 to a worm condenser 30 and thence to a tail house where a suitable receiver 31 separates the water from the gasoline. The number of fractional separators used may vary according to the number or kind of fractional distillates desired. 80

Each clarifying separator has a draw-off pipe 12 at its bottom leading to a cooling coil 32 which acts to cool the particular separation passing therethrough under the pressure maintained in each clarifying separator before discharging into a water separator 18 in the tail house, from whence the various separations are delivered by gravity through pipes leading to distant tanks or receptacles, not shown. The delivery of the separations to the tail house being under pressure permits the tail house to be located any distance apart from the main installation. 105

In spraying the vapors obtained from the primary separator —16—, I find it essential to measure accurately the amount of water used in each clarifying separator in order to obtain the desired fractional distillate and to avoid any mal-function in operations. For this purpose I employ a water meter 33 and a regulating valve 34 in each branch of water pipe 35 which terminates in a spraying head or nozzle 36 within the upper end of each clarifying cylinder 23, 25, 26, 27 and 28, respectively. Also the well or drum 37 at the bottom of each clarifying cylinder has a glass column or sight gage 38 to show the amount of fluid passing therethrough, and suitable valves are placed at intervals in the pipes to regulate the flow of the vapors and fluid 110

and maintain a constant pressure in the entire system so as to create a continuous flow of oil and vapors and uninterrupted separations.

5 I also provide a separate set of clarifying and fractional distilling cylinders as described for each primary separator 16 and its complement of oil heaters 4, 5 and 6, and the showing illustrates a commercial installation capable of refining oil on large scale operations with a minimum of labor and cost, using steam at a high temperature and pressure. The residuum derived from the primary separator 16 makes an excellent cylinder stock and so secured is of better quality than it is possible to obtain by any process using direct heat on the containers of the oil in order to secure this product. The oil secured from clarifying cylinders 26, 27 and 28 or in fact from any or all of the clarifying cylinders may be pumped to and through the primary heating coil 8 and subjected again to the waste heat of the furnace or boiler 2 and then treated 25 with the steam again in the same manner as hereinbefore described to obtain fractional distillates, but in that event either a much higher temperature of superheated steam should be used in the oil heaters than in the first instance or the oil pumped through the system more slowly to obtain a higher heating of the oil in order to crack a large percentage of same into a more volatile oil or gasoline suitable for motor fuel for internal 30 combustion engines. Having eliminated the heavy end of the crude originally run through the apparatus I find it is safe to run the distillates through the same apparatus at a temperature of 200 degrees F. or more 35 higher than when running through the crude oil without the danger of coking the oil and fouling the apparatus.

In running either the crude oil or distillates through the apparatus as described the process is continuous and may be run for weeks or months and the apparatus will be as clean and free from coke or carbon at the end of the run as it was at the start. This is due to the fact that the superheated 45 steam surrounding the coils through which the oil passes permits the oil so passing through the apparatus to be subjected to the desired heat and pressure without being subjected at any time to any localized heat spots which is unavoidable where direct 50 heat on the containers of the oil is used and which local heat spots are the cause of the coking and fouling of the apparatus.

Under a given heating condition in the 55 boiler and superheaters, the speed or rate of flow of the oil through the pipes determines the degree of separation in the primary separator, and where a large output of gasoline or a motor fuel oil is desired and a less 60 number of fractional distillates, more oil

may be pumped per hour through the pipes and the water shut off in the clarifying separators. One or more of the clarifying separators may be used and the water shut off in the remainder to limit the number of fractional distillates, while the amount and quality of distillate obtainable from each clarifying separator may also be regulated by the amount of water sprayed therein. In running the distillates through the system instead of crude oil, the distillate should be pumped through the system at a slower speed in order to increase the temperature of the distillates to a cracking point, and this is feasible because the heavier portion or base of the oil, which is more susceptible to coking or carbonization, has already been removed.

The apparatus shown and described herein is further set forth in my divisional application, filed on the 18th day of February 1919, Ser. No. 277,140.

What I claim is:

1. A process of refining oil, consisting in passing a thin body of oil for a short interval through the waste heat discharged from a steam boiler furnace, the temperature of the waste heat and duration of application being limited to prevent coking or burning of any part of the oil, and secondly, in applying the steam from the same boiler to the heated oil until a higher degree of temperature of the oil is obtained, and finally separating the lighter and heavier portions of the heated oil.

2. A process of refining oil, consisting in passing the oil to be refined continuously in a stream through a heater exposed to the waste heat passing from a steam boiler furnace without excessively heating the oil in its passage to the detriment of its component parts; in continuing the heating of the oil by steam generated in the said boiler for longer intervals and at higher temperatures and discharging and atomizing the heated oil in a closed receptacle; and in separating the liquid and volatile parts resulting from such treatment of the oil.

3. A process of refining oil, consisting in superheating steam in a superheater to a temperature of 800° F. or higher and applying the waste heat passing from the superheater furnace to a predetermined length of a stream of flowing oil without coking or carbonizing the oil and then applying the superheated steam to the heated oil while flowing in a stream to raise the temperature thereof and injecting the highly heated oil with a part of the superheated steam into a separator under constant pressure and discharging the liquid and volatile parts of the oil into separate receptacles.

4. A process of refining oil, consisting in passing a body of oil continuously through a heater exposed to the waste heat products

of a steam boiler furnace at temperatures between 500° and 600° F. and then subdividing the heated oil into separate streams and heating each stream to a higher temperature by steam generated in said boiler and superheated to above 800° F., in discharging each stream of oil together with superheated steam at a temperature above 800° F. into independent vessels under a sustained

pressure; in spraying water upon the volatile separations in said vessels; and in delivering the liquid and remaining volatile product in each vessel to separate containers.

Signed at Cleveland, in the county of Cuyahoga, and State of Ohio, this 19th day 15 of December, 1918.

CHAUNCEY BLAIR FORWARD.
